UNITED STATES PATENT OFFICE

133,623

DESIGN FOR A COAT

Herbert M. Frumkes, Lawrence, N. Y.

Application August 1, 1942, Serial No. 107,777

Term of patent 3½ years

To all whom it may concern:

Be it known that I, Herbert M. Frumkes, a citizen of the United States, residing in Lawrence, Long Island, in the county of Nassau, New York State, have invented a new, original, and ornamental Design for a Coat, of which the following is a specification, reference being had to the accompanying drawing, forming part thereof.

I claim:

The ornamental design for a coat, substantially as shown.

HERBERT M. FRUMKES.
